[75] Inventor: Scott W. Demarest, Caledonia, Wis.

Primary Examiner—James Gandy
Assistant Examiner—Cathron B. Matta

[73] Assignee: S. C. Johnson & Son, Inc., Racine, Wis.

[57] **CLAIM**

[**] Term: 14 Years

[21] Appl. No.: 71,204

The ornamental design for an actuator for an aerosol can, as shown and described.

[22] Filed: May 22, 1997

DESCRIPTION

[51] LOC (6) Cl. 09-01

[52] U.S. Cl. D9/448; D9/445

[58] Field of Search D9/435, 444, 445,
D9/447, 448, 452, 453, 454, 300; 220/915;
222/153.1, 153.11, 182, 402.1, 402.14

FIG. 1 is a front perspective view from above and to one side of an actuator for an aerosol can showing the new design; FIG. 2 is a front elevational view of the device of FIG. 1; FIG. 3 is a back elevational view of the device of FIG. 1; FIG. 4 is a left side elevational view of the device of FIG. 1, the right side being a mirror image thereof; and, FIG. 5 is a top plan view of the device of FIG. 1. The bottom of the closure forms no part of the claimed design.
